(57) **CLAIM**

The ornamental design for a toy vehicle, as shown and described.

DESCRIPTION

FIG. 1 is a perspective view from above, to the front and the left side of the new design for a toy vehicle;

FIG. 2 is a perspective view from below, to the rear and to the right side thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

In the drawings, the broken lines are for the purpose of illustrating portions of the article that form no part of the claimed design.

1 Claim, 8 Drawing Sheets
